Primary Examiner — Mimosa De(74) Attorney, Agent, or Firm — Kegler, Brown, Hill & Ritter; James J. Pingor(57) CLAIM

I claim the ornamental design for a vehicle seat, as shown and described.

DESCRIPTION

FIG. 1 is a left, front perspective view of a vehicle seat according to my new design, wherein a right, front perspective view of the vehicle seat shown in FIG. 1 is a mirror image of FIG. 1;

FIG. 2 is a front elevation view of the vehicle seat of FIG. 1; and,

FIG. 3 is a left elevation view of the vehicle seat of FIG. 1. The broken lines shown herein are for illustrative purposes only and form no part of the claimed design.

1 Claim, 3 Drawing SheetsFIG. 1
